GARMENT OR IRONING PRESS

Ernest Davis, Syracuse, N. Y., assignor to The Prosperity Company Inc., Syracuse, N. Y., a corporation of New York

Application October 11, 1929. Serial No. 398,966

12 Claims. (Cl. 68—9)

This invention relates to pressing machines, as garment and laundry pressing machines, and particularly to actuating means therefor, which actuating means includes a toggle, a booster arranged to come into action when the press is closed under little or minimum pressure in order to deliver final heavy pressure regardless of such conditions as the thickness of the work or the padding, whether thick or thin, and the amount 10 of compression, and it has for its object a particularly simple and efficient toggle construction, a portion of which has an endwise movement effected by the booster means.

The invention consists in the novel features 15 and in the combinations and constructions hereinafter set forth and claimed.

In describing this invention, reference is had to the accompanying drawing in which like characters designate corresponding parts in all the 20 views.

Figure 1 is a side elevation of a machine embodying my invention.

Figure 2 is an enlarged sectional view on line 2—2, Figure 1.

Figure 3 is an elevation of the pedal mechanism shown fragmentarily in Figure 1.

The pressing machine here illustrated is of the conventional type in which the cooperating pressing elements or jaws are a stationary buck 1 and 30 a head 2 movable toward and from the buck. The buck 1 is mounted on a suitable bracket or goose neck 3 which is supported on a suitable frame 4. The head 2 is carried by a lever 5 pivoted between its ends at 6 to a standard 7 rising 35 from the frame.

The means for actuating the head comprises a toggle and means for successively straightening the toggle and boosting the toggle to close the press under heavy pressure, and working in 40 the reverse order when the press is opening.

In the illustrated embodiment of my invention, the toggle and booster means are operated by power.

8 and 9 designate respectively the links of the 45 toggle, these being pivoted together at 10, and pivoted at 11 and 12 to the base of the frame and to the rear arm of the lever 5 respectively. One of the links of the toggle as the lower link 9 consists of two sections, as a rod 13 and a head 50 14 slidably mounted on the rod, the head 14 being connected by the pivot 10 to the lower end of the link 8. The head is bifurcated and the opposite arms thereof have bearings on the pivot 10.

The head 14 also has a sleeve or hub portion 15 55 slidable on the rod 13, and the rod is provided

with a fixed shoulder or collar 16 which normally prevents sliding movement downwardly on the rod 13, the head being movable upwardly from its starting position against the action of a spring 17. This spring 17 is located within the sleeve 80 or hub portion 15 of the head 14 and encircles the rod 13 between a head or shoulder 18 on the upper end of the rod and a seat or shoulder 19 within the sleeve portion 15.

Thus, during the movement of the toggle, from 65 folded position, the head 14 cannot slide downwardly on the rod 13 owing to the shoulder or collar 16 but the head is capable of upward sliding movement against the action of the spring 17 when the boosting force is applied to the lower 70 end of the link 8. The toggle is moved from folded to or toward a straightened position in any suitable manner, here shown as by a cylinder 20 having a piston therein, the rod 21 of which is pivoted at 22 to an angularly forwardly 75 extending arm 23 at the upper end of the link 8, this offset arm being provided on a hub or tilt block 24 at the upper end of the link 8 which block has bearings mounted on the pivot 12. The pivot 22 is disposed forwardly toward the press 80 lever pivot 6.

The flow of motive fluid, as compressed air, to and from the cylinder is controlled by a valve within a valve casing 25 having its intake end 26 connected to a suitable source of supply and 85 having a pipe 27 connecting said casing 25 with the intake end of the cylinder 20.

The valve within the casing 25 is a combined intake and exhaust valve of the conventional type used with pressing machines, and is so located 90 that the intake is normally closed and the exhaust open. This valve is operated in any suitable manner as by a treadle 28 pivoted at 29 to the base of the frame to operate the valve stem 30, of the valve within the casing 25, through a 95 lever 31 and a link 32 between the treadle 28 and the lever 31.

The motion of the treadle is transmitted through a compression spring 33. Depression of the treadle 28 permits air to flow from the pipe 26 100 through the casing 25 and pipe 27 to the cylinder 20 to actuate the piston therein, and hence, move the toggle from folded to any one of a number of nearly straightened positions and close the press under little pressure. The piston rod 21 constitutes a reciprocating actuator for the lever 5 and toggle.

Upon release of the treadle 28, the valves are 105 returned to their normal position and hence air is free to exhaust from the cylinder 20 permit- 110

ting the head to open unless the booster means is actuated.

The booster means comprises a lever 34 pivoted at 35 to the frame and having an arm extending between the bifurcations of the head 14 and so located that the lower end of the link 8 comes into engagement therewith when the toggle is moved into any one of a plurality of nearly straightened positions. The lower end of the link 8 and the booster lever are here shown as provided with wedge frictional surfaces which are V-shaped in cross section or have complementary wedge-shaped engaging faces, the arm of the lever 34 being provided with a V-shaped groove 36 extending longitudinally of the booster lever and the lower end of the link 8 being of wedge formation to fit the V-shaped groove. A suitable clearance 37 is provided at the bottom of the groove in order to permit the wedge faces to firmly engage with surface contact.

The booster lever 34 is also actuated preferably by power and the power means here illustrated is a cylinder 38 having a piston therein, the rod 39 of which is pivoted at 40 to the booster lever 34. The flow of motive fluid to and from the cylinder is controlled by valves located in a valve casing 41 conveniently mounted on the frame 4 and the valves are operated to open position by means of a push button 42. Means as a diaphragm within a diaphragm chamber 43 is provided for locking the valves in their operated position. The valves are released or unlocked to open the press by a trip lever 44.

The intake end of the valve casing 41 is connected to a source of working fluid by a suitable feed pipe 45, and the outlet from the valve casing is connected by a pipe 46 with the cylinder 38.

The construction of the valves in the casings 25 and 41 and the operation thereof forms no part of this invention.

Depression of the treadle 28 preliminarily closes the press as before described, and upon the depression of the push button 42, the booster lever 34 will be actuated to close the press under final pressure and the press will be locked in its closed position by the locking action of the valves due to the diaphragm in the diaphragm chamber 43 which is of conventional design.

The pistons in each of the cylinders are single acting and the press is opened when the pressure in the cylinders is released by countersprings 47 connected to the rear arm of the lever 5 and to the lower part of the pressing machine frame 4.

In operation, the press is first closed by depressing the pedal 28 and when the toggle straightens, the push button 42 may be depressed causing the booster lever 34 to be actuated boosting the toggle link 8 and head 14 upwardly against the action of the spring 17. When the push button 42 is operated, the treadle 28 may be released. Upon operation of the trip lever 44 which releases the booster lever 34, the toggle will fold and the press open under the influence of the countersprings 47. Owing to the spring 17, this folding operation is noiseless and without shock, as the spring prevents a violent taking-up of the lost motion between the links 8 and 9 or between the head 14 and the rod 13.

The toggle 8, 13 preferably does not reach a full-straightened or dead-center position and this enables the toggle knee or joint at 10 to more readily break rearwardly to open the press after the force of the motor means is removed from the leverage mechanism. If the buck padding 1 is new and thick, it follows that the lower end of

link 8 does not travel quite so far up on the lever 34, but if the padding is old and worn the link 8 moves further onto the lever. In either event, the press head 2 closes with the same force and power of the motor 20 which is a lower power 80 motor with smaller bore than the motor means 38.

After the link 8 has assumed any one of its possible numerous and pressure-adjusting positions on the rear end of lever 4 to lightly close the press, the high power motor 38 is energized to produce final jaw compression which is substantially constant and does not vary with the changing of the pad 1. The wear and breaking down of the padding 1 and its diminishing thickness, or changing it to new and thick padding, does not materially alter the uniform jaw pressure attained by this invention. Likewise there are no manual-pressure adjusting means for an operator to use and so the ironing-jaw pressure 95 does not vary from that source since it is well known that an operator may or may not properly attend his machine and keep it in adjustment. Thus an advantage exists in this inherently and constantly automatic adjusting means, the operation of which takes place every time the press jaws close so that the press never gets out of adjustment so far as uniform pressure is concerned.

The construction and arrangement of the toggle block and offset arm 24 is also an advantage as will be seen by considering its dotted line open-press position in Figure 1. The pivot 22, offset from the axis of link 8, aids in initially starting the toggle knee 10 toward straightened position. Less power of the closing motor 20 is required to start the straightening action of the toggle when applying the upward thrust at the point 22 instead of directly applying the up-thrust at pivot 12. By connecting the piston rod 115 21 to the offset block pivot 22, there is a pronounced tendency for the toggle center 10 to more easily get started toward press-closing position. This distribution of the force of the low power 120 closing motor provides a smooth, quiet and high speed machine.

The offset block pivot 22 for the low power closing motor 20 has a further distinct advantage which functions when the press is adjacent to its initially closed position. In this position the pivot 22 is substantially to the right of the pivot 12, as shown in Figure 1, from the line of application of power from the low power motor 20, which line of power would be represented by the piston rod 21. As a consequence, there is a positive turning or pivoting effort applied to the link 8 through the pivot 22 to rotate the link 8 in a counter-clockwise direction about the pivot 12. This positive turning effort upon the link 8 brings the end of the link above and into contact with the booster lever 34 at the end of the preliminary closing movement of the press.

What I claim is:—

1. In a pressing machine, cooperating pressing elements, one of which is movable toward and from the other, means for actuating the movable element including a toggle having a movable endwise link, one of the links of the toggle including two sections one of which is slidably endwise relatively to the other and has a shoulder preventing endwise movement in one direction during straightening of the toggle, the slidable section being pivoted to the other link of the toggle, connections between the latter link and the movable pressing element to actuate the lat- 140 145 150

- ter, a spring interposed between the sections, and means for moving the toggle toward straightened position and thereafter thrusting the link connected to the movable pressing element endwise to produce final pressure between the pressing elements after the toggle is in said straightened position. 5
2. In a pressing machine, cooperating pressing elements, one of which is movable toward and from the other, means for actuating the movable element including a toggle having a first and second link, the first link of the toggle including two sections one of which has a bifurcated end pivotally connected with the second link of the toggle and a sleeve slidable endwise on the other section of said first link, operating connections between the second link and the movable pressing element to actuate the latter, an abutment on the first link, a spring located in the sleeve and thrusting the latter against said abutment, and means for successively straightening the toggle and moving the second link endwise, a part of the last mentioned means extending between the bifurcated end and coacting with the adjacent end of the second link. 10
3. In a pressing machine, cooperating pressing elements, one of which is movable toward and from the other, means for actuating the movable element including a toggle having a first and second link, the first link of the toggle including two sections one of which has a bifurcated end pivoted to the second link of the toggle and a sleeve slidable endwise on the other section of said first link, connections between the second link and the movable pressing element to actuate the latter, an abutment on the first link, a spring located in the sleeve and thrusting the sleeve portion of the head against said abutment, and means for successively actuating the toggle toward straightened position and moving the second link endwise, a part of the last mentioned means extending between the bifurcations of the head and coacting with the adjacent end of the second link and having frictionally coacting wedge faces. 15
4. In a pressing machine, cooperating pressing elements, one of which is movable toward and from the other, means for actuating the movable element including a toggle having a first and second link, the first link of the toggle including two sections one of which has a bifurcated end pivoted to the second link of the toggle and a sleeve slidable endwise on the other section of said first link, operating connections between the second link and the movable pressing element to actuate the latter, an abutment on the first link, a spring located in the sleeve and thrusting the latter against said abutment, and means for successively actuating the toggle toward straightened position and moving the second link endwise, a part of the last mentioned means extending between the bifurcated end and coacting with the adjacent end of the link, said part having frictionally coacting wedge faces of V-shaped formation. 20
5. In a pressing machine, cooperating pressing elements, one of which is movable toward and from the other, means for actuating the movable element including a toggle having an endwise movable portion, a spring for resisting said endwise movement, means for actuating the toggle toward straightened position, booster means carried by the frame for thereafter forcing said portion endwise, and the booster means and the endwise portion having coacting wedge shaped engaging faces. 25
6. In a pressing machine, a frame, cooperating pressing elements one of which is movable toward and from the other, a lever carrying the movable element, toggle links pivoted together and respectively to the frame and to said lever, the link pivoted to the lever having an angularly extending arm near the end thereof adjacent the lever, and a reciprocating actuator connected to said arm. 30
7. In a pressing machine, a frame, cooperating pressing elements, one of which is movable toward and from the other, a lever carrying the movable element, toggle links pivoted together and respectively to the frame and to said lever, the link pivoted to the lever having an angularly extending arm near its end adjacent the lever, a reciprocating actuator connected to said arm, the link connected to said lever being shiftable endwise relatively to the other link, and booster means for effecting the endwise movement of the link connected to said lever. 35
8. A garment or ironing press comprising a frame and coacting press jaws, a lever fulcrumed in the frame and carrying one jaw to actuate it in relation to the other jaw, a link pivotally connected to the lever and having an offset arm disposed toward the fulcrum, link means operatively mounted in the frame and connected with the link to guide its movement, and motor means pivotally connected with the offset arm. 40
9. A garment or ironing press comprising a frame supporting a press jaw, a press lever fulcrumed in the frame and carrying another press jaw, a toggle pivoted at one end on the frame, a pivot directly connecting the other end of the toggle to the lever, a second pivot carried by the toggle at its end connected with the lever, said second pivot being disposed proximate the first pivot and between said first pivot and the fulcrum, and means operatively connected with the second pivot to thrust it upwardly to impart a straightening action to the toggle and a swinging motion to the press lever. 45
10. A pressing machine comprising coacting press jaws, a frame, a lever fulcrumed on the frame and attached to one jaw, a toggle including an upper link secured to a hub which is pivotally connected with the lever and a lower link pivoted on the frame, said links being operatively connected at their adjacent ends to provide a toggle knee which swings relatively to the frame to fold and straighten the toggle, an arm formed on the hub and extending at an angle to the upper link and towards the fulcrum of the lever, and operating means connected with the arm on a pivot disposed proximate the hub pivot in the lever, whereby the force of the operating means acts initially to tilt the hub and thereby actuating the knee toward straightened position and actuates the lever to close the press. 50
11. A garment or ironing press comprising a frame and coacting press jaws, a lever fulcrumed in the frame and carrying one jaw to actuate it in relation to the other jaw, a link pivotally connected to the lever and having an offset arm disposed toward the fulcrum, booster means normally spaced from operative position with the link, link means operatively mounted in the frame and connected with the link to guide its movement into operative relation with the booster means upon closing of the press to apply heavy pressure thereto, and motor means pivotally connected with the offset arm to close the press under 55

light pressure and swing the link into operative position with the booster means.

12. A garment or ironing press, comprising a frame, cooperating pressing jaws one of which is movable with respect to the other to open and close the press, actuating mechanism for the movable pressing jaw including an extendible toggle, a booster lever pivoted between its ends on the frame, means for closing the press and moving

the toggle into substantially straightened position with a portion thereof overlying one end of the booster lever, and complementary interlocking faces on the booster lever and that portion of the toggle overlying the booster lever for holding the toggle in substantially straightened position during the boosting thereof. 80
